SAFETY STARTER

Irwin S. Jacobsen, Little Falls, N. J., assignor to
 Industrial Electronics Corporation, Newark,
 N. J., a corporation of New Jersey

Application January 27, 1948, Serial No. 4,603

11 Claims. (Cl. 200—113.5)

1

The present invention is concerned with safety starting devices and with circuits incorporating the same for the protection of gaseous electric discharge equipment such as fluorescent lamps of the hot cathode type.

It is among the objects of the invention to provide a safety device of the above type which is relatively inexpensive, compact and economical in operation, requiring a minimum of parts, all of which are contained in a single sealed unit and which lends itself for use with fluorescent lamps and the conventional fixtures thereof as a replacement for starters of conventional type, which device utilizes but a single resistance to control the safety action and when incorporated in a starting circuit does not draw current when the lamp is functioning normally and which operates dependably and promptly without floating between the contacts thereof to preclude the repeated application of starting current to a defective lamp and to avoid the annoyance of continuous flashing of the defective lamp after the first few starting impulses have been applied thereto and which automatically restores itself, promptly to permit normal operation of a new lamp substituted for the defective one, and the efficacy of which is not affected by variations in the ambient temperature, thereby safeguarding the lamp from the destructive effect of repeated starting effort without undue strain upon the device itself.

According to the invention, a gas filled bulb is provided in which is contained all of the operating parts of the safety starting device, including a glow switch starter having a conventional bimetallic arm which forms one of the electrodes thereof, a heat responsive switch arm which functions as the other electrode of the glow switch starter, and a safety resistor which is connected at one end to said heat responsive switch arm.

The safety starting device is connected with the bimetallic arm thereof in series with one of the electrodes of the gaseous electric discharge device which it controls, a ballast coil and one of the current mains, and the free end of the safety resistor is connected in series with the other electrode of the gaseous electric discharge device and the other current main.

In the embodiment herein shown, the safety resistor is in circuit only when it is attempted to operate a defective lamp and remains out of circuit at all other times throughout the operation of a normally functioning lamp.

In response to the heat evolved in the bulb by the glow in the gap between the two electrodes,

2

after repeated attempts of the glow switch starter to start a defective lamp, the switch arm will be displaced, thereby removing the short circuit from the safety resistor immediately to bring it into action. The heat evolved in the gap and in the safety resistor will continue to displace the switch arm until it engages the bimetallic arm also displaced by the heating effect of the glow and the added heat from the safety resistor.

Continued current through the safety resistor, which is preferably of high ohmic value, produces sufficient heat to retain the bimetallic arm and switch arm in deflected position and in engagement with each other so that the glow switch starter is effectively removed from the closed circuit until the circuit is opened, as by replacement of the defective lamp.

In the accompanying drawings in which are shown one or more of various possible embodiments of the several features of the invention,

Fig. 1 is a view of the safety starting unit in longitudinal cross section,

Fig. 2 is a fragmentary perspective view on a larger scale of the unit with the casing removed,

Fig. 3 is a view similar to Fig. 2 of another embodiment of the device, and

Fig. 4 is a circuit diagram showing the safety starter circuit common to both embodiments herein.

Referring now to the drawings, there is shown in the diagrammatic view of Fig. 4 a conventional gaseous electric discharge device 10 of the hot cathode type such as a fluorescent lamp including a pair of electrodes 11 and 12 at opposite ends thereof. One of the mains 13 connected to electrode 11 has a ballast coil 14 in series therewith, while a switch 15 is shown in the other main 16, the latter being connected to electrode 12.

The safety starting device 17 which is incorporated in the starting circuit has all of its elements contained in a glass envelope or bulb 18 filled with an inert gas such as neon. The device has a pair of terminals 19 and 21 which are connected to electrodes 11 and 12, respectively, of the lamp 10 by leads 22 and 23.

The safety device 17 comprises a starter 25 preferably of the glow switch type, one of the electrodes of which, preferably the bimetallic arm 26 as shown, is connected to terminal 19 by lead 46.

The safety device 17 also includes a bimetallic switch arm 27, one end 28 of which is connected to one end of a resistor 29 as at 31. The free

contact end 32 of the switch arm 27 is movable between the contact end 33 of bimetallic starter arm 26 and a contact bar 34 connected to the other end of resistor 29 as at 36 and thence by lead 47 to terminal 21. The contact end 32 of the switch arm 27 normally engages contact bar 34 so that resistor 29 is normally short circuited.

A condenser 35 is provided across terminals 19 and 21 to prevent arcing of the starter contacts when the device is in use.

When switch 15 is closed, the line voltage will be applied across the electrodes 11 and 12 of the lamp 10 and across terminals 19 and 21. As the applied voltage is at the outset insufficient to cause arcing of the lamp 10 but sufficient to cause glow switch starter 25 to ionize across the gap 30 between contacts 32 and 33 thereof, current will flow through the circuit, storing energy in the ballast coil 14. The path of current through the circuit will be through main 16, electrode 12, lead 23, terminal 21, lead 47 to contacts 34 and end 32 of switch arm 27 across the gap 30, contact end 33 of bimetallic arm 26 through said arm 26, lead 46 to terminal 19, lead 22, electrode 11, ballast coil 14 and main 13. The heat developed by the ionization of the gas in the bulb 18 across gap 30 will bring contacts 32 and 33 together to close the gap 30, thereby stopping the glow. As soon as the glow ceases, the bimetallic arm 26 will cool and deflect, thereby causing the contacts 32 and 33 to separate. This will break the starting circuit through the electrodes 11 and 12 and the ballast coil 14, causing the energy which has been stored in the latter to discharge through the circuit. This sudden impulse should bridge the gap between the now heated electrodes in the lamp 10 and start the arc, causing the lamp to light. Since the arc when once maintained requires voltage less than that required to initiate the glow discharge in the gap 30, the glow switch starter 25 will remain out of action and the starting circuit is broken, due to the gap 30 between contacts 32 and 33. If the lamp is in normal condition, one or two cycles of the glow switch should light it.

At the same time that the glow switch starter 25 is ionized, but before the lamp lights, the heat generated by the glow in the gap 30, in addition to causing bimetallic arm 26 to deflect, will also be dissipated to the bimetallic switch arm 27 which is slower acting than arm 26. If the lamp is defective, continued cycles of the glow switch starter 25 will produce sufficient heat to increase the temperature in bulb 18 to such a degree as to cause switch arm 27 to deflect so that the contact end 32 thereof is moved out of engagement with contact bar 34, thereby removing the short circuit about resistor 29. The latter will immediately draw current, the circuit being from main 16, electrode 12, lead 23, terminal 21, lead 47, through resistor 29, switch arm 27, contact end 32 thereof, across the ionized gap 30, contact end 33 of bimetallic arm 26, through said arm, lead 46, terminal 19, lead 22, electrode 11, ballast coil 14 and main 13.

By reason of the heat dissipated by the current flowing through resistor 29 and the heat caused by the glow in gap 30, bimetallic arm 26 and switch arm 27 will deflect toward each other until the contact ends 32 and 33 thereof respectively are in engagement, closing gap 30 and placing resistor 29 directly across lamp electrodes 11 and 12.

Continued passage of current through resistor 29 will produce sufficient heat in the bulb 18 to

retain switch arm 27 and bimetallic arm 26 in deflected position and maintain contact ends 32 and 33 thereof together, thus eliminating the gap 30 and effectively removing the starter 25 from the circuit to prevent any further cycling thereof, thereby preventing the fluorescent lamp from starting. It is apparent that the effective removal of the glow switch starter 25 will occur if the lamp does not light after a few cycles.

10 Thus the rapid destruction of the glow switch starter 25, due to many repetitions of the starting cycle on a defective lamp, is avoided. Shortly after the circuit is broken by the opening of switch 15, resistor 29 will cool and allow switch 15 arm 27 and bimetallic arm 26 to revert to their normal position shown in Fig. 4, in readiness for normal operation with a replacement lamp.

Inasmuch as the bimetallic arm 26 and switch arm 27 require but little heat in order that they 20 be maintained in deflected position, resistor 29 is preferably of high ohmic value so that only a small amount of current will be consumed by the device. Resistor 29 is desirably of carbon, 25 preferably glazed to prevent absorption of the neon or other inert gas in the bulb with changing temperature therein.

Thus when glow switch starter 25 is effectively removed from the circuit by switch arm 27 when the lamp is defective, and resistor 29 is placed 30 across the electrodes 11 and 12, the resistor 29 will draw but little current.

Safety starter units incorporating the starting and safety controls of the circuit shown in Fig. 4 and above described are shown in Figs. 1, 2, and 3 of the drawings wherein the numerals used in the circuit diagram of Fig. 4 are employed for corresponding elements. Referring to the embodiment shown in Figs. 1 and 2, the unit, which is connected across leads 22 and 23 from electrodes 11 and 12 respectively, comprises an insulating base 41 with two terminals 19 and 21 depending therefrom and a metal cover or cap 42 having tabs 43 removably to secure it to base 41. The cap 42 has an insulating liner 44 covering its side wall and 45 a further insulating liner disk 45 for its top wall. In the unit is enclosed the glass bulb 18 which is filled with a noble gas, such as neon for instance, and has leads 46 and 47 extending through the pinched end 48 thereof which seals the bottom of the bulb. The upper ends of the leads 46 and 47 in the bulb are connected to supports 49 and 51, respectively, by a drop of glass as at 52. Affixed to support 49 is a U-shaped electrode 26, of bimetallic material responsive to variations in temperature. Affixed to support 51 is a contact bar 34 spaced from the contact end 33 of bimetallic arm 26. A resistance 29, preferably carbon as shown, but alternatively a wire resistance or the like is affixed at one end to support 51 preferably by soldering and extends upwardly therefrom. The upper end of resistance 29 has a bimetallic switch arm 27 affixed thereto as at 31 and extending downwardly therefrom spaced from the resistance 29 and substantially parallel thereto. The switch arm 27 has a contact end 32 which normally engages contact bar 34 and is spaced from the bimetallic arm 26.

A capacitor 35 is positioned outside the bulb and connected across the terminals 19 and 21 by 70 leads 53 and 54 to prevent arcing of the contacts of the unit.

It will be understood that the spring tension of switch arm 27 is such as to maintain the contact end 32 thereof against contact bar 34 even 75 at the highest ambient temperature encountered.

in any place where a fluorescent lamp is normally used or which is generated by the heat of a normally operating lamp.

In the embodiment of the device shown in Fig. 3 in which similar parts have the same reference numerals primed, a mount 55 is affixed to the upper end of resistor 29' as at 31' extending downwardly therefrom and parallel thereto. Switch arm 27' which is made substantially U-shaped to conserve space, is affixed as at 28' to the lower end of mount 55 and extends laterally therefrom encompassing resistor 29 with the contact end 32' of switch arm 27' normally in engagement with contact bar 34'.

By this construction the overall length of the unit may be less, which is an important factor when space is limited.

Thus it can be seen that when the lamp is operating normally, the safety starting device is completely out of circuit and no current is consumed thereby and with a defective lamp in circuit only the resistor 29 draws current and as its ohmic value is high, will consume but a minimum of current.

The unit is simple in construction, requiring but few parts and hence is relatively inexpensive. It is thoroughly reliable in operation, inasmuch as once the switch arm 27 leaves the contact bar 34, resistance 29 will heat to move contact end 32 into engagement with contact end 33 to stop the repeated starting of a defective lamp without danger of hunting or floating of switch arm 27.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A safety starting and operating circuit, contained in a gas filled bulb for gaseous electric discharge lamps equipped with spaced electrodes, said circuit comprising a glow discharge type starter in said bulb, said starter comprising a pair of starting contacts normally spaced from each other and forming a gap therebetween, a heat responsive arm carrying one of said contacts, connected at one end in said starting circuit, a heat responsive switch arm in said bulb connected at one end in said starting circuit and carrying the other of said starting contacts, said starter evolving sufficient heat in the attempted starting of a defective lamp for displacement of said switch arm to bring said starting contacts into engagement, thereby closing said gap, and heating means in said bulb, normally out of circuit and connected in series with said starting circuit and said switch arm when the latter has brought said contacts into engagement and closed said gap after said attempted starting of such defective lamp, to maintain said switch arm in displaced condition as long as the operating circuit remains closed.

2. A safety starting and operating circuit, contained in a gas filled bulb for gaseous electric discharge lamps equipped with spaced electrodes, said circuit comprising a glow discharge type starter in said bulb, said starter comprising a pair of starting contacts normally spaced from each other and forming a gap therebetween, a heat responsive arm carrying one of said contacts,

connected at one end in said starting circuit, a heat responsive switch arm in said bulb in close proximity to said first named heat responsive arm, connected at one end in said starting circuit and carrying the other of said starting contacts, a resistor in said bulb in said starting circuit, normally short circuited by said switch arm, said starter evolving sufficient heat in the attempted starting of a defective lamp for displacement of said switch arm to remove the short circuit across said resistor and place the latter in series with said starting circuit, and for bringing said starting contacts into engagement, thereby closing said gap, the heat evolved by said resistor maintaining said switch arm in displaced condition as long as the operating circuit remains closed.

3. A safety starting and operating circuit, contained in a gas filled bulb for gaseous electric discharge lamps, equipped with spaced electrodes, said circuit comprising a glow discharge type starter in said bulb operatively connected in said circuit intermittently to interrupt the latter, said starter comprising a pair of starting contacts normally spaced from each other and forming a gap therebetween, a heat responsive arm carrying one of said contacts, connected at one end in said starting circuit, a heat responsive switch arm in said bulb in close proximity to said first named heat responsive arm, connected at one end in said starting circuit and carrying the other of said starting contacts, a resistor in said bulb in said starting circuit and normally short circuited by said switch arm, said starter evolving sufficient heat in the attempted starting of a defective lamp for displacement of said switch arm to remove the short circuit across said resistor and place the latter in said starting circuit, and for bringing said starting contacts into engagement, thereby closing said gap and stopping the intermittent interruption of said starting circuit, the heat evolved by said resistor maintaining said switch arm in displaced condition as long as the operating circuit remains closed.

4. A safety starting and operating circuit, contained in a gas filled bulb for gaseous electric discharge lamps equipped with spaced electrodes, said circuit comprising a heat responsive glow discharge starter means in said bulb operatively connected in the circuit intermittently to interrupt the latter, a heat responsive switch arm in said bulb, a resistor in said circuit normally short circuited by said switch arm, said switch arm, after repeated attempts to start a defective lamp, being deflected by the heat evolved by said glow discharge starter to remove the short circuit from said resistor and place the latter in circuit, said switch arm being further deflected by the continued operation of said glow discharge starter and the heat evolved by said resistor, effectively to remove said glow discharge starter from the circuit, said resistor evolving sufficient heat to maintain said switch arm in deflected position, thereby stopping the intermittent interruption of said starting circuit.

5. A safety starting and operating circuit, contained in a gas filled bulb for gaseous electric discharge lamps equipped with spaced electrodes, said circuit comprising a glow discharge type starter in said bulb, said starter comprising a bimetallic arm having a contact thereon and a second contact normally spaced therefrom and forming a gap therebetween, a heat responsive switch arm in said bulb carrying said second contact, and connected at one end in said starting

circuit, a resistor in said bulb normally short circuited by said switch arm, said starter evolving sufficient heat in the attempted starting of a defective lamp for displacement of said switch arm to remove the short circuit across said resistor and place it in series with said starting circuit, and for bringing the contact on said switch arm into engagement with the contact on said bimetallic arm, thereby closing said gap, the heat evolved by said resistor maintaining said switch arm in displaced condition, effectively to remove the starter from the circuit as long as the operating circuit remains closed.

6. A safety starting and operating circuit for a gaseous electric discharge lamp equipped with spaced electrodes, said circuit comprising heat evolving means automatically to interrupt said circuit to strike an arc between said electrodes, and means to preclude the sustained intermittent starting of a defective lamp, said latter means comprising a thermally operated switch arm in circuit with said heat evolving means and normally disconnected therefrom, a safety resistor in said starting circuit normally short circuited by said switch arm, said switch arm being deflected by the heat evolved in said heat evolving means in the attempted starting of a defective lamp to remove the short circuit across said safety resistor, the heat evolved by said safety resistor and said heat evolving means in the continued attempted starting of a defective lamp deflecting said switch arm further into engagement with said heat evolving means, effectively to remove the latter from the circuit, thereby preventing further attempts to start said defective lamp.

7. The combination set forth in claim 6 in which said resistor alone evolves sufficient heat to maintain said switch arm in deflected position.

8. A self-contained safety starter device for a gaseous electric lamp, said device comprising a gas filled bulb having a pair of leads therein extending therefrom, a bimetallic arm in said bulb connected to one of said leads, a resistance in said bulb connected at one end to the other of said leads, a heat responsive switch arm connected at one end to the free end of said resistance, the free end of said switch arm being normally in electrical contact with the opposite end of said resistance and spaced from the free end of said bimetallic arm and movable thereagainst, the space between the free ends of said switch arm and said bimetallic arm forming a glow discharge gap.

9. The combination set forth in claim 8 in which a support base is provided having a pair of terminal posts to which the extending ends of said leads are respectively connected.

10. A self-contained safety starter device for a gaseous electric lamp, said device comprising a gas filled bulb having a pair of leads therein extending therefrom, a bimetallic arm in said bulb connected to one of said leads, an upstanding resistance in said bulb connected at its lower end to the other of said leads, a heat responsive switch arm connected at one end to the upper end of said resistance and extending downwardly and substantially parallel to said resistance, the free end of said switch arm being normally in electrical contact with the lower end of said resistance and spaced from the free end of said bimetallic arm and movable thereagainst, the space between the free ends of said switch arm and said bimetallic arm forming a glow discharge gap.

11. A self-contained safety starter device for a gaseous electric lamp, said device comprising a gas filled bulb having a pair of leads therein extending therefrom, a bimetallic arm in said bulb connected to one of said leads, an upstanding resistance in said bulb connected at its lower end to the other of said leads, a mount affixed to the upper end of said resistance and extending downwardly therefrom substantially parallel to said resistance, a U-shaped heat responsive switch arm affixed at one end to the lower end of said mount, extending laterally therefrom and encompassing said resistance, the free end of said switch arm being normally in electrical contact with the lower end of said resistance and spaced from the free end of said bimetallic arm and movable thereagainst, the space between the free ends of said switch arm and said bimetallic arm forming a glow discharge gap.
